(57) **CLAIM**

The ornamental design for an upright power terminal, as shown and described.

DESCRIPTION

FIG. 1 is a perspective view of an upright power terminal with a first component and a second component along one direction, and shows relative positions between the first component and the second component;

FIG. 2 is a perspective view of the upright power terminal along the other direction, and shows the relative positions between the first component and the second component;

FIG. 3 is a front, top, and right side perspective view of the first component showing my new design;

FIG. 4 is a front plane view thereof;

FIG. 5 is a back plane view thereof;

FIG. 6 is a left side view thereof;

FIG. 7 is a right side view thereof;

FIG. 8 is a top plan view thereof; and

FIG. 9 is a bottom plan view thereof;

FIG. 10 is a front, top, and right side perspective view of the second component showing my new design;

FIG. 11 is a front plane view thereof;

FIG. 12 is a back plane view thereof;

FIG. 13 is a left side view thereof;

FIG. 14 is a right side view thereof;

FIG. 15 is a top plan view thereof; and,

FIG. 16 is a bottom plan view thereof.
